UNITED STATES PATENT OFFICE.

JOSEPH LANE WRIGHT, OF WASHINGTON, DISTRICT OF COLUMBIA,
ASSIGNOR TO THE NATIONAL ENGINEERING CORPORATION, OF
WASHINGTON, DISTRICT OF COLUMBIA, A CORPORATION OF THE
DISTRICT OF COLUMBIA.

TELEPHONE-SWITCHBOARD LAMP.

No. 829,092.

Specification of Letters Patent. Patented Aug. 21, 1906.

Application filed May 10, 1905. Serial No. 259,728.

To all whom it may concern:

Be it known that I, JOSEPH LANE WRIGHT, a citizen of the United States, residing at Washington, in the District of Columbia, have invented certain new and useful Improvements in Telephone - Switchboard Lamps, of which the following is a specification, reference being had therein to the accompanying drawings.

10 My invention relates to incandescent lamps, and more especially to that type used for line-signals in telephone-switchboards.

In switchboards of the type now in almost universal use a series of line-lamp-jack strips are arranged in tiers on the switchboard in front of the operator with their contact ends passed through the board and only the faces thereof showing. Below each strip of lamp-jacks are placed the line-plug jacks, which 20 correspond with the lamp-jacks above. It will be also understood that the same arrangement is made regarding the supervisory signals, and in both cases the lamps of the line and supervisory signals are almost impossible to get at. At present when a lamp is burned out or otherwise rendered useless the trouble man or a special switchboard man has to be called to repair the wrong. The lamp-jacks are of necessity very small 25 and the space between the lamp-bulb and the jack is consequently so, and as it is impossible to remove the lamps from the back of the switchboard and the repair man has to do all the work from the front a pair of special 30 pliers are used to grasp the smooth surface of the lamp-bulb to remove the lamp. My invention is designed to obviate all these difficulties and to provide means whereby any person can attend to this matter without 35 special trouble.

My invention is illustrated in the accompanying drawings, in which—

Figure 1 is a side elevation of a lamp inclosed in a jack, the jack being shown in section. Fig. 2 is a side elevation of the lamp removed from the jack. Fig. 3 is a side elevation of a modification. Fig. 4 is a side elevation of a further modification. Fig. 5 is a top plan view thereof.

50 In Fig. 1 of the drawings, 1 represents a lamp-jack of the ordinary type which is sub-

stantially cylindrical in cross-section and which is provided with an entirely-inclosed portion 2, within which lies the lamp-bulb 3. The jack is provided with an interior insulating-sleeve 4 and the usual contacts 5 and 6, the latter suitable spring metal. The contacts are held separated in the casing 1 by an insulating-block 7. The above construction in no way forms any part of my invention, except inasmuch as the parts co-operate with the lamp to make a complete device.

Referring to Figs. 2 and 3, 3 represents the lamp-bulb, as in Fig. 1, to which are secured the lamp-contacts 8 and 9, which partially surround the bulb 3 and which are insulated apart by an insulating-block 10. These contacts are, as usual, properly secured to the terminal ends of the lamp-filaments. One or both of the contact members 8 and 9 is provided with a projecting end 11, which extends along the side of the bulb 3 and slightly past its end, where it is bent into a tongue or lip 12. In Fig. 2 I have shown the projecting end 11 on one contact only, while in Fig. 3 each contact is provided with this projection 11 and lip 12.

In Figs. 4 and 5 the same style of lamp is shown as in Figs. 1, 2 and 3; but instead of the lip 12, as in Figs. 2 and 3, I have shown the projecting end 11 provided with an aperture 13.

Any suitable sort of tool may be used to extract the bulb, such as a wire bent similar to a shoe-hook or with two legs having hooked ends.

It will be evident that I could make many changes in construction without departing from the spirit of the invention. For instance, the projecting end of the contact 11 (shown in Figs. 4 and 5) may be placed on each side. Any form of lamp might be used, and the projecting member may be connected with the bulb in any suitable manner.

It will be observed that the tongues 12 nor the projecting members 11 in no way obscure the light from the lamp, and by practical test it has been shown that the difference cannot be noticed between lamps having this device and lamps without it when shielded behind the translucent number-plates of the jacks.

Having thus described my invention, what

I claim, and desire to secure by Letters Patent, is—

1. An incandescent lamp having means independent of the bulb for facilitating its removal from its socket.
2. An incandescent lamp comprising a bulb and contacts, one or more of said contacts provided with means for facilitating the removal of the lamp from its socket.
3. An incandescent lamp comprising a bulb and contacts, one or more of said contacts provided with a projecting member adapted to facilitate the removal of the lamp from its socket.
4. An incandescent lamp comprising a bulb and contacts, one or more of said contacts provided with a projecting member having means to facilitate the removal of the lamp from its socket.

tacts provided with a projecting member, said projecting member having means to facilitate the removal of the lamp from its socket.

5. An incandescent lamp comprising a bulb and lamp-contacts, one or more of said lamp-contacts provided with an integral projecting member, and a transverse tongue on said member.

In testimony whereof I affix my signature in presence of two witnesses.

JOSEPH LANE WRIGHT.
